UNITED STATES PATENT OFFICE

108,511

DESIGN FOR A TEXTILE FABRIC

William Harm, Philadelphia, Pa.

Application January 26, 1938, Serial No. 74,550

Term of patent 3½ years

To all whom it may concern:

Be it known that I, William Harm, a citizen of the United States of America, residing in the city of Philadelphia, State of Pennsylvania, have invented a new, original, and ornamental Design for a Textile Fabric, of which the following is a specification, reference being had to the accompanying drawing, forming part thereof, wherein,

The figure is a plan view of a piece of textile fabric showing my new design.

I claim:

The ornamental design for a textile fabric substantially as shown.

WILLIAM HARM.
